UNITED STATES PATENT OFFICE

FRANK COLLINS, OF NEW YORK, N. Y., ASSIGNOR TO METROPOLITAN LAMP CO., INC.,
OF NEW YORK, N. Y.

DESIGN FOR A LAMP BASE MEMBER OR ARTICLE OF SIMILAR NATURE

Application filed July 25, 1930. Serial No. 36,470. Term of patent 3½ years.

To all whom it may concern:

Be it known that I, FRANK COLLINS, a citizen of the United States, residing in New York, in the county of New York and State of New York, have invented a new, original, and ornamental Design for a Lamp Base Member or Article of Similar Nature, of which the following is a specification, reference being had to the accompanying drawing, forming a part thereof.

The figure is a perspective view of a lamp base member showing my new design. The ornamentation shown in full lines is repeated about the body of the article.

I claim:

The ornamental design for a lamp base member, or article of similar nature, as shown and described.

In testimony whereof I affix my signature.
FRANK COLLINS.
